BY *Victor J. Evans* ATTORNEY

UNITED STATES PATENT OFFICE.

HENRY HATCHET, OF THOMASVILLE, GEORGIA.

DESIGN FOR A CANE.

• 56,722.

Specification for Design.

Patented Dec. 7, 1920.

Application filed July 12, 1920. Serial No. 395,776. Term of patent 14 years.

To all whom it may concern:

Be it known that I, HENRY HATCHET, a citizen of the United States, residing at Thomasville, in the county of Thomas and State of Georgia, have invented a new, original, and ornamental Design for a Cane, of which the following is a specification, reference being had to the accompanying drawing, forming a part thereof.

The figure is a perspective view of the cane, showing my new design.

I claim:—

The ornamental design for a cane as shown.

HENRY ^{his} X HATCHET.
